(57) CLAIM

The ornamental design for a bottle, as shown and described.

DESCRIPTION

FIG. 1 is a front elevational view of a bottle, showing our new design, the rear elevational view being a mirror image thereof;

FIG. 2 is a right side elevational view thereof, the left side elevational view being a mirror image thereof;

FIG. 3 is a top plan view thereof;

FIG. 4 is a bottom plan view thereof; and,

FIG. 5 is a front, left side perspective view thereof, shown in a reduced scale.

The broken line portions show unclaimed subject matter only and form no part of the claimed design.
